CLAIM

The ornamental design for a display screen or portion
thereof with graphical user interface, as shown and
described.

DESCRIPTION

The file of this patent contains at least one drawing/photograph
executed in color. Copies of this patent with color
drawing(s)/photograph(s) will be provided by the Office
upon request and payment of the necessary fee.

FIG. 1 is a front view of a display screen or portion thereof
with graphical user interface showing the claimed design;
and,

FIG. 2 is a front view of another embodiment of a display
screen or portion thereof with graphical user interface.

The peripheral dashed broken lines illustrate a display
screen or portion thereof, and form no part of the claimed
design.

1 Claim, 1 Drawing Sheet
